UNITED STATES PATENT OFFICE.

GEORGE RITTER, OF WOODBRIDGE, NEW JERSEY, ASSIGNOR TO THE BARBER ASPHALT COMPANY OF PHILADELPHIA, PENNSYLVANIA, A CORPORATION OF WEST VIRGINIA.

SHINGLE.

Application filed September 21, 1925. Serial No. 57,485.

This invention relates broadly to roof coverings and the like while it is more particularly associated with the fabrication of a novel type of shingle from sheet material treated with weather-proofing substance to render the same impervious to the ravages incident to constant exposure.

An object of the present invention is to provide a novel form of shingle which, when laid, affords a uniform multi-ply thickness over the surface covered, while the weather edges will produce a pleasing architectural finish incident to an increased depth afforded by the shadow lines.

Another object of this invention is to provide a shingle devoid of unprotected edges whereby the durability thereof is materially increased and the deteriorative effects arising from atmospheric exposure correspondingly reduced.

A further object is to furnish a novel form of shingle which, when diagonally laid in successive rows, interlocks with the subjacent ones so as to effectively prevent "lifting" by heavy winds or other causes.

A still further object is to provide shingles of the above designated type which give added protection against fire hazards that may originate thereunder.

With the above stated—and other—objects in view, the present invention essentially consists in the matters hereinafter fully described, typically exemplified by the accompanying drawings, and circumscribed as to subject-matter, as well as scope, by the subjoined claims.

In the drawings:—

Fig. I, is a view in plan showing the blank from which my novel type of shingle is formed, and also indicating, by dot-and-dash outline, the manner in which it is severed from standard width material without waste.

Fig. II, is a face view of the finished shingle.

Fig. III, is a rear view of the same.

Fig. IV, is a top plan view of a fragmentary portion of a roof covered with my novel type of shingles; and,

Fig. V, is a section taken approximately on the line V—V in the preceding view.

Referring more in detail to the several views, wherein the same or corresponding parts are designated by like reference in-

dices, and in carrying out my invention, I 55 preferably make use of sheet material—such as roofing felt—rendered flexible, non-porous and weather proof in accordance with customary practice. Such a sheet or length of material is indicated at 6, in Fig. I, and it 60 is preferably of a width to accommodate the depth of shingles required, and finished on one side with a suitable mineralized surfacing imbedded therein. This length or roll of roofing material 6 is transversely severed 65 at regular intervals to provide individual shingle blanks 7 that are consecutively cut in reverse relation without waste, as shown.

Each aforesaid blank 7, as best appreciated from Figs. I—III, comprises a body or substantially-square shingle portion 8 minus the upper diagonal corner that provides a straight edge 9; a pair of flanking triangular portions 10, 10 foldable along creasings 11 aligning with the lower shingle side edges 12; and a butt-tab 13 retroverted along a basal crease 14 while separated from the triangular portions 10, 10 by vertical incisions 15, 15. The flanking triangular portions 10, 10, it will be remarked, are of a superficial configuration, so that, when retroverted along the creases 11 against the underside—or non-mineralized surface—of the body portion 8, their bases 16 register with the vertical median line thereof with their free 75 inclined edges 17 moved into parallelism relative to the upper side edges 18 of said shingle. In other words, the folded shingle 8 becomes two-ply for the major portion of its area with a triple-ply at that portion 90 constituted by the retroverted butt-tab 13. Attention is also directed to the fact that the major portion of the shingle underside is protected—and fireproofed—by the mineralized surfacing of the underfolded flanking 95 portions 10, 10.

Shingles formed and configured as above set forth are laid in the following manner:—

A starting strip 19 is first attached to a straight or longitudinal edge of the roof or other surface boarding 20 in conformity with known practice, whereupon a succession of shingles 8 are conveniently secured in place by nails—not shown—with the butt-tabs 13 forced below said starting strip, and their contiguous rectangular corners 21 in register; or, all such corners of the first row are arranged in direct alignment. Thus

it will be readily understood that the upper straight edges 9 of the first row of shingles 8, so laid, will—likewise—be in direct alignment. The second or succeeding row of overlapping shingles 8 is laid by inserting the butt-tab 13 of each consecutive shingle underneath the contiguous rectangular corners 21 of a subjacent pair of shingles and aligning the upper side edges 18 thereof with the relatively spaced obtuse-angled corners 22 of said subjacent pair of shingles; or, in staggered relation relative to the first mentioned row. Nails or other attaching means are then applied where necessary or deemed essential. It will, therefore, be readily understood that the individual shingles 8 are interengaged and securely locked against any tendency to lift under wind or other pressures; while all the exposed edges thereof—excepting those at the ends of the surface covered—are constituted by folded material at the creasings 11, 11 and 14. This feature of my invention is deemed of considerable importance inasmuch as it effectively protects all the raw or severed edges from deterioration incident to climatic exposure. Again, the multi-ply thickness afforded by the pre-ordered connection of the respective shingle units above set forth greatly enhances the shadow-line effects, as will be clearly apparent to those acquainted with the art. Successive overlapping rows of the shingles 8 are similarly laid and nailed in staggered diagonal relation, in accordance with common practice until the entire roof or other surface is covered and finished in the known manner; while attention is directed to the fact that the obtuse-angled corners 22 afford aligning points for successively laid superposed shingles, as will be obvious from an examination of Fig. IV.

Having set forth the manner of fabricating and laying my novel shingles attention is now directed to some of the leading advantages inhering thereto. In the first place, it will be apparent that the entire surface covered with shingles 8 is of a minimum double-thickness throughout with a substantial mineralized inner surfacing as a protection against fire originating under the roof deck or the like. Secondly, all weather exposed edges being coated and surfaced, are thoroughly protected from deterioration. Furthermore, the shingles 8 may be made from relatively thinner stock than ordinarily used in the art while affording a better protective covering without materially increasing the weight per "square."

From the foregoing it will be apparent that my novel type of shingle fully justifies the objects set forth in the statement of invention, and while it is preferable to employ

the embodiment illustrated, it is to be understood the same is susceptible of modification to accord with individual requirements. 65

Having thus described my invention I claim:

1. A shingle having a butt-tab and flanking foldable portions which, when retroverted, substantially convert said shingle to 70 double-ply thickness.

2. A shingle having a butt-tab and flanking foldable portions, said foldable portions when retroverted forming a double-ply thickness shingle with upper-flanking single-ply portions and of triple-ply at the lower tip. 75

3. A shingle having a corner tab and flanking foldable portions, said foldable portions when retroverted substantially backing 80 the shingle, and the tab overlapping the contiguous folds.

4. A flexible shingle having a corner tab and triangular side portions, the latter when retroverted substantially backing the shingle, 85 and the aforesaid tab forming a locking tongue.

5. A point-down flexible shingle having one corner configured to afford a rectangular butt-tab, and adjoining triangular foldable 90 flanks, said flanks when retroverted backing the shingle with provision of upwardly merging single-ply portions.

6. A point-down flexible shingle having one corner configured to afford a rectangular 95 butt-tab, and adjoining triangular foldable flanks, said flanks when retroverted backing the shingle with provision of upwardly merging single-ply portions, and the butt-tab overlapping the contiguous underfolds. 100

7. A flexible shingle of substantially square outline having one corner removed and the diagonally opposed corner affording a rectangular butt-tab, and underfoldable 105 triangular side portions integral with said shingle adapted to substantially back the same.

8. As an article of manufacture a shingle blank embodying a substantially square body portion with a butt-tab at one corner, and retrovertible adjoining flanks which, when underfolded, substantially back said shingle. 110

9. As an article of manufacture a shingle blank embodying a substantially square body portion with a butt-tab at one corner, and retrovertible adjoining flanks which, when underfolded, substantially back said shingle with provision of merging single-ply sections. 115

In testimony whereof, I have hereunto signed my name at Maurer, New Jersey, this 15th day of September, 1925. 120

GEORGE RITTER.
